Klemchuk LLP(57) **CLAIM**

The ornamental design for an inverted bellow, as shown and described.

DESCRIPTION

FIG. 1 is a top, side perspective view of an inverted bellow;
 FIG. 2 is a top view thereof;
 FIG. 3 is a bottom view thereof;
 FIG. 4 is a right side view thereof;
 FIG. 5 is a left side view thereof;
 FIG. 6 is a distal end view thereof;
 FIG. 7 is a proximal end view thereof;
 FIG. 8 is a top view of the inverted bellow in an unassembled state; and,
 FIG. 9 is a top side perspective view thereof.
